UNITED STATES PATENT OFFICE.

CLEON W. SCHULTZ, OF SCRANTON, PENNSYLVANIA, ASSIGNEE TO H. W. JOHNS-
MANVILLE COMPANY, A CORPORATION OF NEW YORK.

SUSPENDED INSULATOR.

983,573.

Specification of Letters Patent. Patented Feb. 7, 1911.

Application filed January 3, 1910. Serial No. 536,110.

To all whom it may concern:

Be it known that I, CLEON W. SCHULTZ, a citizen of the United States of America, residing at Scranton, county of Lackawanna, 5 State of Pennsylvania, have invented certain new and useful Improvements in Suspended Insulators, of which the following is a specification.

My invention relates to electrical insulators generally, and more specifically consists of an improved suspended insulator for trolley wires and the like electrical conductors. Insulators for this character of work, when employed in mines, for instance, are supported from various different kinds of overhead structures, according to the nature of the mine galleries and headings along which the wires run. Sometimes the insulators are attached directly to wooden beams supporting the roof of the gallery or tunnel. Sometimes, when the roof is high, they are supported from pipes hanging down from the high roof timbers, or from pipe brackets extending out horizontally from side timbers or supports. Heretofore, a differently shaped insulator has been required for fastening to each of these different supports and it is the object of my invention to produce one standard form of insulator which 30 can be attached equally well and conveniently to all the usual different forms of overhead supports.

The best form of apparatus embodying my invention at present known to me is illustrated in the accompanying two sheets of drawings in which,

Figure 1 is a side elevation of my insulator attached to a depending pipe end. Fig. 2 is a central vertical section of same attached to a barbed screw bolt such as may be driven into timber. Fig. 3 is a plan view of the insulator. Fig. 4 is a side elevation and partial section of the insulator with sleeve attachment for engaging a horizontal pipe arm or bracket, and Fig. 5 is an end elevation of the sleeve.

Throughout the drawings like reference numbers indicate like parts.

1 is the usual bell shaped shell generally 50 made of metal and containing a body of molded insulating material 2, in which is embedded any fastening member 3 to which the clip or hanger proper (not shown) may be attached.

55 In the upper portion of the shell 1 is a

centrally disposed opening 4, tapped out to receive and engage with a screw threaded bolt 5. The opening 4 may have an enlargement 6 at the bottom for receiving a certain amount of dirt which may be stripped off the threads by the entering bolt.

Around the upper portion of the shell 1 is formed an annular recess 7, which may be concentric with the opening 4 and adapted to receive a depending pipe end 8 (see Fig. 1) which may be clamped in position by set screws 9, 9, or any other convenient holding means.

The upper portion of the shell 1 may be given an octagonal exterior form, as shown in Fig. 3, or other shape such that it may be conveniently grasped by a wrench when it is to be screwed on to or off from a bolt, as 5.

10 represents a portion of a horizontal pipe bracket or arm on which is the metal sleeve 11, held in any position by set screw 12, or other holding means, and having the screw threaded projection 13, adapted to engage the tapped opening 4, of the shell 1. The sleeve also has a flange 14 around the screw threaded projection 13, adapted to cover and overlap the annular recess 7 in the shell.

In operation but one form of insulator is needed for attachment to the various supports shown, whether the barbed anchor bolt 5 driven into a timber, a hanging pipe end 8, or the horizontal bracket and sleeve shown in Fig. 4. The sleeve 11 may be adjusted on the bracket by loosening the set screw 12, 90 and the flange 14 protects the annular recess 7 from being filled up with dirt, and water forming rust, when the horizontal bracket support is used.

Having, therefore, described my invention, I claim:

1. In a suspended insulator for trolley wires and the like electrical conductors the combination of a shell for holding insulating material provided with an opening in the upper portion tapped to receive a supporting screw threaded bolt, an annular recess to receive the end of a supporting depending pipe, and means for retaining said pipe end in said recess.

2. In a suspended insulator for trolley wires and the like electrical conductors a shell for holding insulating material and a support embedded therein, the shell being provided on its upper face with a central

opening tapped to receive a supporting screw threaded rod, an annular recess surrounding the opening adapted to receive the end of a supporting depending pipe, and set screws for clamping said pipe end in said recess.

3. In a suspended insulator for trolley wires and the like electrical conductors, the combination of a shell adapted to contain insulating material provided with an opening in its upper portion tapped to receive a screw threaded bolt, and an annular recess concentric with said opening adapted to receive the end of a supporting depending pipe and means for retaining said pipe end in said recess, together with supporting means provided with a screw threaded projection adapted to engage said tapped opening and with a flange around said screw threaded projection which overlaps the annular recess in the shell when the last mentioned supporting means is employed.
4. In a suspended insulator for trolley wires and the like electrical conductors, the combination of a shell adapted to contain insulating material provided with an opening in its upper portion tapped to receive a screw threaded bolt, and with an annular recess concentric with said opening adapted to receive the end of a supporting depend-

ing pipe and means for retaining said pipe end in said recess, together with a cylindrical sleeve adapted to slip over a horizontal arm and provided with a screw threaded projection adapted to engage said tapped opening, the said sleeve being provided with a flange around the screw threaded projection adapted to overlap the annular recess in the shell.

5. In a suspended insulator for trolley wires and the like electrical conductors the combination of a shell adapted to contain insulating material provided with an opening in its upper portion tapped to receive a screw threaded bolt, and with an annular recess concentric with said opening adapted to receive a vertical tubular support, and provided with means for grasping said support, and a cylindrical sleeve adapted to slip over a horizontal arm and provided with a screw threaded projection adapted to engage said tapped opening, said sleeve being provided with a flange around the screw threaded projection adapted to overlap the annular recess in the shell.

CLEON W. SCHULTZ.
